UNITED STATES PATENT OFFICE.

HENRY E. VAN NESS, OF ELMIRA, NEW YORK.

DYEING APPARATUS.

Application filed April 3, 1923. Serial No. 629,633.

To all whom it may concern:

Be it known that I, HENRY E. VAN NESS, a citizen of the United States, residing at Elmira, in the county of Chemung and State of New York, have invented certain new and useful Improvements in Dyeing Apparatus, fully described and represented in the following specification and the accompanying drawings, forming a part of the same.

This invention relates to apparatus for impregnating parts of an absorbent mass with a liquid.

This application is a continuation in part of my previous application filed October 7, 1922, Serial No. 592,964 (on which U. S. Patent No. 1,456,844 was issued to me on May 22, 1923) in so far as it embodies the disclosure of said application. In that application I described a method of dyeing textiles, apparatus for carrying out said method, and articles of manufacture produced thereby. I have invented an improved apparatus useful for carrying out said method and for other purposes and improved articles of manufacture which may be made by the said method. The present application embodies substantially all the disclosure of my aforesaid application, and in addition a disclosure of said improved apparatus and improved articles of manufacture. The present application is directed particularly to dyeing apparatus including both the apparatus disclosed in my aforesaid application and improvements in such apparatus. The articles of manufacture disclosed in my aforesaid application and improvements therein form the subject matter of my co-pending application Serial No. 723,430, filed June 30, 1924, as a division of the present application.

A feature of the invention is to provide apparatus for injecting, under pressure, a limited quantity of liquid into an absorbent mass so as to form a stream of the liquid extending into the mass and to arrange this apparatus so that this stream of dye may be free to expand laterally throughout its length by absorption into the pores of the mass.

A further feature of the invention consists in apparatus for supplying and injecting measured quantities of liquid under pressure,

A further feature of the invention consists in providing a holder for the mass to be impregnated, and means for causing relative approaching and separating movements between this holder and the injecting apparatus, as well as means for stopping the approaching movements when the injecting apparatus is in operative relation to the mass on the holder.

A further feature of the invention consists in a method of forming long spots on a yarn wound into a mass in a regular manner by a plurality of injections of dye into the mass. The invention includes, also, means for varying the relative positions of a holder for the mass of yarn and an injecting apparatus, which may be used to carry out this method.

In order that the invention may clearly be understood, I will describe in detail a practical yarn-dyeing machine embodying a combination of all the apparatus features of the invention to which reference has been made, as well as additional features hereinafter noted. Such a machine is illustrated in the accompanying drawings, in which—

Fig. 1 is a plan view of the machine;

Fig. 2 is a side view of the machine sectioned on line 2—2 of Fig. 1;

Fig. 3 is a transverse section of the machine taken on the line 3—3 of Fig. 1;

Fig. 4 is a developed view of the face of the guide wheel of the work holder;

Fig. 5 is an enlarged fragmentary vertical section taken on the line 5—5 of Fig. 3 and showing a portion of the guide wheel and the spring-pressed ball which cooperates with it;

Fig. 6 is an enlarged view of the upper portion of the pump partially sectioned on the line 6—6 of Fig. 1 and showing the operating lever in raised position;

Fig. 7 is a similar view showing the operating lever partly depressed;

Fig. 8 is an enlarged axial section of the pump and the injector taken on a plane at right angles to the section plane of Figs. 6 and 7;

Fig. 9 is a perspective view of the clutch which holds the needle of the injector;

Fig. 10 is a perspective view of the needle;

Figs. 11 and 12 are side views of a cone of yarn after it has been spotted in the machine;

Fig. 13 is a diagrammatic view indicating the position of the spots on a development of the surface of the cone of yarn;

Fig. 14 is a side view, partly in section, showing a modified injector;

Fig. 15 is a similar view showing another form of injector; and

Fig. 16 is an enlarged transverse section taken on the line 16—16 of Fig. 15.

10 The yarn spotting machine shown in the drawings comprises a base plate B, on which are mounted a dye tank T, a pump P and a work holder W. In the use of the machine, a cone C of yarn is supported on the work holder W, and measured quantities of liquid dye from the tank T are forced into the cone by the pump P through an injector J, which is mounted on the cylinder of the pump.

20 The pump P has a cylinder P¹, which has at its lower end a flange P², which is bolted to the base plate B. The lower portion of the cylinder P¹ serves merely as a support for the operative parts of the pump and contains a large axial bore P³ to reduce its weight. The upper portion of the pump cylinder P¹ contains a smaller axial bore, the lower end of which is closed by a plug P⁴. The portion of the smaller bore above the plug P⁴ provides a chamber P⁵ into which liquid dye flows from the tank T and from which measured quantities of the dye are expelled under pressure. The chamber P⁵ is provided with an inlet opening P⁶, an air vent opening P⁷ and a discharge opening P⁸. The outer end of the inlet opening P⁶ is connected by a pipe P⁹ with an opening T¹ near the bottom of the tank T. The outer end of the opening P⁷ communicates with an open vent pipe P¹⁰. The discharge opening P⁸ communicates with apparatus J for directing liquid dye into a mass of yarn supported on the work holder W. This apparatus, which for the sake of brevity, I term an injector, is hereinafter described in detail. An opening P¹¹ in the cylinder wall near the lower end of the chamber P⁵ places this chamber in communication with a closed compression chamber P¹². In the form illustrated, the compression chamber P¹² is formed by an elbow pipe P¹³ and a pressure gauge P¹⁴ of ordinary construction, which serves to close the outer end of the pipe P¹³.

40 The inlet opening P⁶, the air vent opening P⁷ and the discharge opening P⁸ are controlled by a valve sleeve P¹⁵ containing ports P¹⁶, P¹⁷ and P¹⁸ which register with these openings respectively in certain positions of the valve sleeve. The valve sleeve is thrust upward by a compression spring P¹⁹ reacting between the lower end of the sleeve and the plug P⁴. A pin P²⁰ projecting through the wall of the cylinder P¹ into a longitudinal slot P²¹ in the valve sleeve prevents turning of the sleeve and limits the upward movement of the sleeve under the thrust of

the spring P¹⁹. A plug P²² is secured in the upper end of the valve sleeve P¹⁵. This plug normally projects above the top surface P²³ of the cylinder P¹ and has at its upper end a cam surface P²⁴.

70 The plunger P³⁰ of the pump fits within the valve sleeve P¹⁵. The plunger is mounted on a rod P³¹ which extends through the plunger. The lower end of this rod enters an axial bore P³² formed in an axial extension P³³ of the plug P⁴. The upper end of the rod P³¹ passes through an axial bore in the plug P²² and normally projects beyond the upper end of this plug. The rod has at its upper end a cam surface P³⁴. Rotation of the 75 plunger rod P³¹ in the sleeve P¹⁵ is prevented by a key P³⁵ fixed in the rod and engaging a key-way P³⁶ in the plug P²². The plunger P³⁰ is thrust upward by a compression spring P³⁷ surrounding the lower portion of the rod P³¹ and reacting between the lower end of the plunger and the upper end of the axial projection P³⁸ of the plug P⁴.

80 The valve sleeve and the plunger of the pump are operated by means of a double cam P⁴⁰ providing a central cam surface P⁴¹ which engages the cam surface P³⁴ at the upper end of the plunger rod P³¹, and two spaced cam surfaces P⁴² which engage the cam surface P²⁴ of the upper end of the 85 plug P²² which is fixed in the valve sleeve P¹⁵. The cam P⁴⁰ is fixed on a shaft P⁴³, which is rotatably mounted in two ears P⁴⁴ which extend upwardly from the upper end of the cylinder P¹. The shaft P⁴³ and the 90 cam P⁴⁰ may be turned about their axes by means of an operating lever P⁴⁵, which may be formed integral with the cam P⁴⁰, as shown.

95 In operating the pump, the operating lever 100 P⁴⁵ is oscillated between its raised position shown in Fig. 6 and a lowered position in which a projection P⁴⁶ on the cam P⁴⁰ engages the cylinder P¹ at P⁴⁷. The downward movement of the lever may be caused 105 manually, while its return or upward movement is most desirably caused by a spring. I find that the most convenient way to provide for the operation of the lever P⁴⁵ is to connect it to a foot pedal of usual construction located under a table on which the base plate of the machine is supported. Such a pedal is indicated diagrammatically at P⁴⁸ in Fig. 1. The return movement of the 110 lever P⁴⁵ may be caused by the usual spring-return mechanism used with foot pedals. A spring for causing the return movement is 115 diagrammatically illustrated at P⁴⁹ in Fig. 1.

120 The operation of the pump is as follows: When the operating lever P⁴⁵ is in raised 125 position, the cam P⁴⁰, the valve sleeve P¹⁵ and the plunger P³⁰ occupy the positions shown in Figs. 6 and 8. The valve ports P¹⁶ and P¹⁷ register with the inlet opening P⁶ and the air vent P⁷, respectively, so that 130

liquid dye flows by gravity from the tank T into the chamber P⁵ and fills the chamber. During the filling, the air which was contained in the chamber escapes through the 5 vent pipe P¹⁰.

During the first part of the downward movement of the operating lever P⁴⁵, the portion P⁵⁰ of the cam surfaces P⁴² engages the cam surface P²⁴ and depresses the 10 sleeve P¹⁵, while the portion P⁵¹ of the cam surface P⁴¹ engages the cam surface P³⁴ and depresses the plunger P³⁰. The downward movement of the plunger is a little 15 more rapid than that of the sleeve. The initial downward movement of the sleeve closes the inlet opening P⁶ and the air vent opening P⁷, and as soon as this occurs the downward movement of the plunger forces a portion of the liquid dye confined in the 20 chamber P⁵ into the lower part of the compression chamber P¹², compressing the air trapped therein. The liquid dye in the chamber P⁵ is, therefore, placed under an 25 increasing pressure as the plunger descends.

When the sharply inclined portion P⁵² of the cam surfaces P⁴² engages the cam surface P²⁴, the sleeve P¹⁵ is given a sudden short downward movement which brings its port P¹⁸ into register with the discharge opening P⁸, thus opening the discharge opening instantaneously. The downward movement of the sleeve then ceases, owing 30 to the fact that the portion P⁵³ of the cam surfaces P⁴² is concentric with the shaft P⁴³. The downward movement of the plunger continues after the sleeve has stopped and becomes very rapid, owing to the inclination of the portion P⁵⁴ of the 35 cam surface P⁴¹.

On the opening of the discharge opening P⁸ liquid is ejected from the chamber P⁵ by the pressure stored in the compression chamber P¹². The pressure on the liquid is maintained during its discharge by the final 40 rapid descending movement of the plunger. As a result, a measured quantity of liquid, that is, the amount displaced by the movement of the plunger, is ejected from the chamber P⁵ under pressure and almost 45 instantaneously.

On the return or upward movement of the operating lever P⁴⁵, the described movements of the plunger and sleeve are reversed. The initial rapid upward movement of the 50 plunger, while the sleeve remains stationary with its port P¹⁸ in register with the discharge opening P⁸, causes an inward suction through the discharge opening. When the upward movement of the lever is completed, the plunger and sleeve are again in 55 filling position.

The movement of the operating lever P⁴⁵ of the pump is utilized to stir the dye in the tank T so as to prevent a separation of

the ingredients of the dye. For this purpose, a stirrer consisting of a propeller T² is placed in the tank T. The hub T³ of the stirrer is rotatably mounted on a vertical shaft T⁴. A ratchet T⁵ pinned to the shaft T⁴ engages ratchet teeth formed on the lower side of the hub T³ and transfers rotation of the shaft T⁴ in one direction to the propeller. The shaft T⁴ is connected with the shaft P⁴³ by bevel gears T⁶, so that the oscillatory movements given to the shaft P⁴³ by the operating lever P⁴⁵ are transferred to the shaft T⁴. The rotation of the shaft T⁴ which is caused on downward movements of the operating lever P⁴⁵ is transferred to the propeller by means of the ratchet T⁵. On upward movements of the lever P⁴⁵, the ratchet T⁵ slips under the ratchet teeth of the propeller hub T³, so that the propeller does not retard the upward movement of the operating lever and the parts connected with it.

Apparatus is provided for directing the limited quantities of liquid which are ejected from the pump into a mass of yarn supported on the work holder. Such apparatus I have, for the sake of brevity, termed an ejector. It may consist merely of a nozzle, by which term I designate any device providing a discharge opening for directing liquid in a predetermined direction. A feature of the invention consists, however, in forming the injector so that it opens a narrow passage into the mass and directs the liquid into the mass through this passage. In order that the mass may be dyed evenly throughout all or a considerable portion of its depth, the injector is formed to permit lateral expansion of the shaft of liquid injected into the mass throughout the depth of the injection. The injector is formed also to prevent the liquid from spreading over the surface of the mass around the point at which it is injected.

In the form illustrated in Figs. 8, 9 and 10, the injector J comprises a nozzle J¹ and a needle J² fixed in the discharge opening of the nozzle. The nozzle J¹ has a body J³, on the rear end of which is a threaded stem J⁴, which is screwed into a tapped hole P⁵⁵ in the cylinder P¹. This hole P⁵⁵ communicates with the discharge opening P⁸ but is not co-axial therewith. The projection J⁴ contains an axial bore J⁶, which is the intake opening of the nozzle J¹. The central portion of the body J³ of the nozzle provides a flange J⁸ which is seated against the boss P⁵⁶ on the cylinder P¹. In an enlarged bore in the front portion of the body J³ is located a chuck J¹⁰ containing an axial bore J¹¹ which forms the discharge opening of the nozzle J¹. The chuck J¹⁰ is retained in the body by a nut J¹² which is screwed on the front end of the body and engages the chuck

⁵ ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰

J^{10} so as to force the conical inner end J^{13} of the chuck against a conical seat in the body. The chuck J^{10} has at its outer end a flat contact surface J^{14} which is thrust against the surface of the mass to be dyed when the mass is brought into operative relation with the injector. On the outer end of the nut J^{12} is a stop J^{15} providing an annular surface J^{16} lying in substantially the same plane as the contact surface J^{14} and spaced therefrom.

The needle J^2 has its rear end inserted in the axial bore J^{11} of the chuck J^{10} . It is retained in the chuck by contracting the chuck by screwing the nut J^{12} inward. As the shaft of the needle is of uniform diameter, it may be gripped at any point by the chuck. It follows that the distance which the needle projects beyond the contact surface J^{14} may be adjusted, and that after an adjustment is made and the nut J^{12} is screwed in tightly, the needle is held in fixed relation to this contact surface. The fact that the hole P^{55} is not co-axial with the discharge opening P^8 , so that the intake opening J^6 of the nozzle is not in alignment with this opening, eliminates all danger of bringing the needle into contact with the sleeve P^{15} by thrusting its rear end too far inward.

The needle J^2 has a pointed front end J^{18} , the apex of which is on the axis of the needle. The needle is formed to provide a longitudinal passage J^{19} which extends substantially its entire length and communicates with the discharge opening J^{11} of the nozzle. The needle is formed to permit lateral egress from this passage throughout substantially the entire length of the projecting portion of the needle. In the form of injector shown in Figs. 8 and 10, such egress is permitted by giving the longitudinal passage J^{19} the form of an open groove. Provision for lateral egress of the liquid in a needle having an axial longitudinal passage such as the needle $J^{2''}$ shown in Figs. 15 and 16 is made by providing a plurality of lateral openings J^{20} in the wall of the axial passage $J^{19''}$. In such case the lateral openings J^{20} are positioned all along the portion of the needle which is thrust into the mass in making an injection.

A feature of the invention consists in turning the open side of the groove J^{19} of the needle J^2 in such direction that the strands of the mass into which the needle is thrust are not drawn tightly over the groove so as to obstruct the egress of liquid therefrom. To accomplish this purpose, the open side of the groove J^{19} is turned in a direction as nearly as possible parallel to the lay or lays of the yarn in the mass to be impregnated, or, in other words, by turning the needle so that the groove lies in a transverse plane of the wound mass of yarn. As the work holder W of the machine illus-

trated, which is hereinafter described in detail, is adapted to hold the core of a wound mass of yarn with its axis horizontal, the needle J^2 is secured in the chuck J^{10} in such manner that the open side of the groove J^{19} is turned either directly up, as shown in the drawing, or directly down.

Means are provided for preventing the liquid which is forced into the injector from spreading over the surface of the mass into which it is to be injected. In the form of injector shown in Fig. 8, the contact surface J^{14} at the outer end of the nozzle serves this purpose when it is pressed firmly against the surface of the mass.

The modified injectors J' and J'' , shown in Figs. 14 and 15, respectively, are not formed to provide contact surfaces similar to the contact surface J^{14} , but embody a different means for preventing the liquid from spreading over the surface of the mass. The needle $J^{2'}$, shown in Fig. 14, has a longitudinal passage which consists of an open groove $J^{19'}$ extending the greater part of the length of the needle, and a closed passage J^{21} at the rear end portion of the needle. This closed passage is preferably of greater cross-section than the open groove. When an injection is made with the injector J' , the needle $J^{2'}$ is thrust into the mass to such an extent that the closed passage J^{21} extends slightly inside the surface C^1 of the mass (indicated by a dotted line in Fig. 14). When the needle is in this relation to the mass, the walls of the closed passage J^{21} serve to prevent a spreading of the liquid over the surface of the mass.

The needle $J^{2''}$, shown in Fig. 15, is similar to the needle $J^{2'}$, except that the open groove $J^{19'}$ is replaced by an axial passage $J^{19''}$ provided with a plurality of lateral openings J^{20} . When an injection is made with the injector J'' , the needle $J^{2''}$ is thrust into the mass to such an extent that the rear-most of the openings J^{20} is within the surface C^1 of the mass.

Specific features of the modified injector shown in Fig. 15 are not claimed herein, as they form subject-matter of my divisional application filed December 30, 1925, Serial No. 78,323.

The work holder W is adapted to support a wound mass of yarn for movement towards and away from the injector to bring the mass into and out of operative relation to the injector. These movements are in directions parallel to the axis of the injector, i. e., of its discharge opening J^{11} , and consequently parallel to the needle J^2 of the injector. The work holder also permits movements of the surface of the mass in directions transverse to the needle J^2 , so that different points of the surface of the mass may be brought opposite the injector. Means are provided for arresting the latter

movements so as to provide for bringing predetermined points of the surface opposite the injector.

The work holder illustrated is adapted to support a cone of yarn. This expression, "cone of yarn", is used herein in its conventional sense to indicate a hollow frusto-conical mass of yarn wound on a frusto-conical core. Such cones of yarn are usually cross-wound, having two lays at an angle to each other. Such a cone usually has a convex surface at its larger end and a concave surface at its smaller end.

To support such a cone, the work holder 15 W is provided with a shaft W^1 , on one end of which is an expansion clutch W^2 adapted to grip the hollow core C^2 of a cone C of yarn and to hold the cone coaxial with the shaft. The clutch W^2 is operated by a lever 20 W^3 connected with it by a push rod W^4 lying in an axial bore in the shaft W^1 .

The shaft W^1 is mounted on a standard W^5 , which projects up from a plate W^6 . The shaft W^1 is mounted so that its axis and 25 the axis of the cone C lie in the same horizontal plane as the needle J^2 . The shaft is inclined to the needle at such an angle that the cone's surface C^1 , which is towards the injector, is substantially perpendicular to 30 the needle J^2 .

In order to provide for movement of the cone towards and away from the injector, the plate W^6 is slidably mounted on two bars W^7 , which extend parallel to the needle J^2 . The bars W^7 are mounted on a frame W^8 , which is mounted on the base plate B of the machine in the manner hereinafter described. A lever W^{10} is provided for causing sliding movements of the plate W^6 on the bars W^7 . This lever is pivoted at W^{11} to a cross piece W^{12} secured to the ends of the bars W^7 and has a pin and slot connection with an arm W^{13} extending from the outer end of the plate W^6 . An adjustable stop W^{14} is provided for limiting inward movements of the plate W^6 . This stop is set to prevent the plate W^6 from moving inward to an extent sufficient to bring the point J^{18} of the needle J^2 into contact with 50 the shaft W^1 or the clutch W^2 , as such contact would injure the point on the needle. The stop W^{14} is, however, not used to arrest the inward movements of the plate W^6 in the ordinary operation of the machine, 55 as the stop J^{15} accomplishes this purpose.

The work holder permits movements of the surface of the cone C in directions perpendicular to the needle J^2 . Two movements of this sort are provided for. One is a bodily movement of the cone in the direction of the side C^1 of the cone which is adjacent to the injector. Such movement is provided by mounting the frame W^8 , which carries the bars W^7 , so that it may slide

across the base plate B of the machine. 65 For this purpose, the frame W^8 is mounted on two cross bars W^{16} and W^{17} , whose ends are held in projections B^1 formed on the upper surface of the base plate B . The frame W^8 may be slid along these bars by 70 means of a lever W^{17} which is pivoted to the base plate B at W^{18} and has a slot and pin connection with the frame W^8 at W^{19} . In order to arrest the sliding movement of the frame W^8 at predetermined points, the cross bar W^{16} is provided with recesses W^{20} and 75 W^{21} , and the frame W^8 carries a spring-pressed plunger W^{22} having a pointed end adapted to enter either of these recesses. The cross bar W^{16} is held against longitudinal movement on the base plate B by a set screw W^{23} . By loosening this screw, the longitudinal position of the bar may be adjusted to vary the positions in which the motion of the frame W^8 is arrested by the 80 means described.

A further movement of the surface of the cone C is permitted by mounting the shaft W^1 on the standard W^5 in such manner that the shaft is free to rotate. Means are provided for arresting rotary movement of the shaft at predetermined points. For this purpose, a guide wheel W^{30} is mounted on the shaft W^1 near its outer end. The guide wheel W^{30} is detachably fixed on the shaft by means of a set screw W^{29} . The guide wheel has an outer cylindrical surface containing a groove W^{32} . In this groove are depressions W^{33} . On an arm W^{34} projecting horizontally from the plate W^6 is supported a spring-pressed ball W^{35} which engages the groove W^{32} of the guide wheel W^{30} . The ball W^{35} is seated at the upper end of a vertical bore W^{36} in the arm W^{34} and urged upwardly by a spring-pressed plunger W^{37} . A pin W^{38} on a plug W^{39} screwed into the lower end of the bore W^{36} serves to limit the downward movement of the ball so as to prevent it from slipping out of the groove W^{32} . The ball is given 100 sufficient freedom of vertical movement to enable it to enter and move out of the depressions W^{33} .

A feature of the invention, which is not claimed herein as it forms the subject matter of my divisional application filed December 30, 1925, Serial No. 78,322, consists in a method for obtaining long spots on a yarn by injecting dye into a mass of the yarn wound in any regular manner. A yarn having spots whose length is no greater than the width of the portion of a mass of the yarn which may be dyed by a single injection of dye may, by means of certain types of knitting machines, be formed into a fabric having an attractive mixed appearance. I have found, however, that when other types of knitting machines are used, it is neces- 110 115 120 125

sary, in order to produce an attractive fabric, that the spots on the yarn be several inches in length.

My method of obtaining long spots consists in injecting dye into a wound mass of the yarn at a series of points lying along a lay of the yarn and separated by such distances that the portion of the mass dyed by the injection at one point contacts with, but does not materially overlap, the portion of the mass dyed by the injection at the next point. In applying this method to cross-wound cones of yarn, I make injections at each point of several different series of points and locate the points of one series along one lay of the yarn of the cone and the points of another series along another lay of the yarn of the cone. When a cone of yarn which has been dyed by this method is unwound, it is found that long spots have been formed on the yarn.

A further feature of the invention, embodied in the machine illustrated, consists in providing a work holder adapted for use in carrying out this method of dyeing. For this purpose, the shaft W^1 is mounted on the standard W^6 in such manner that it is free to move axially as well as to turn about its axis, and the groove W^{32} in the guide wheel W^{30} is formed to provide a plurality of helical portions which extend parallel to the lays of the yarn of the cone. In the form illustrated, the groove W^{32} has two helical portions W^{40} , W^{41} parallel to one lay of the yarn and one helical portion W^{42} parallel to the other lay of the yarn. The ends of these three helical portions of the groove are spaced from each other, and are joined by connecting portions W^{43} , so that the groove W^{32} extends all the way around the circumference of the guide wheel. The depressions W^{33} are spaced regularly along each of the helical portions W^{40} , W^{41} , W^{42} of the groove, while the connecting portions W^{43} of the groove contain no depressions.

The use of the machine which has been described is as follows:

A cone C of the yarn to be spotted is first placed on the work holder W . This is done when the lever W^{10} is thrown to the right, as shown in Fig. 1, so that the shaft W^1 is as far as possible from the needle J^2 . The hollow core C^2 , on which a cone C of yarn is wound, is slipped over the clutch W^2 , while the lever W^8 is turned out to permit contraction of the clutch W^2 . The lever W^3 is thrown into the position shown in Fig. 3 to expand the clutch and lock the core on the shaft W^1 .

The lever W^{10} is then thrown to the left, moving the cone C towards the injector J and causing the needle J^2 to penetrate the cone of yarn in a direction perpendicular to the cone's surface C^1 which is opposite the injector. The movement of the cone of

yarn and the plate W^6 is arrested when the surface C^1 of the cone C comes in contact with the surface J^{16} of the stop J^{15} . As the mass of yarn is compressible, the plate W^6 is not brought to rest until the part of the mass which is brought against the stop J^{15} is somewhat compressed, as shown by the dotted line in Figs. 2 and 8. When the motion of the plate W^6 is stopped, the contact surface J^{14} at the end of the nozzle J^1 is pressed firmly against the surface of the cone C , compressing the cone somewhat where it is in contact with it; and the needle J^2 has penetrated the cone of yarn nearly, or quite, to the core C^2 . Since the core is usually made of cardboard, the needle is not injured if its point is forced into the core to some extent.

A measured quantity of liquid dye is then injected into the cone of yarn by depressing the pump lever P^{45} . The injected dye penetrates to the core C^2 of the cone before any substantial part of it is absorbed into the pores of the yarn. The injection thus results in forming a shaft of dye extending into the cone of yarn in the passage opened by the needle J^2 . This shaft of dye then spreads, by absorption, into the portion of the cone adjacent to the needle throughout the length of the shaft of dye injected. The portion of the cone colored by the dye is approximately cylindrical in shape and extends from the outer surface of the cone to the core in a direction perpendicular to a plane tangent to the outer surface at the point where the injection is made. The dyed portion is of substantially the same cross-sectional area throughout its depth.

The pump lever P^{45} is released as soon as it has been pressed all the way down. During the upward movement of the lever, any liquid dye which may remain in the nozzle or the needle of the injector is sucked back into the pump chamber P^6 , so that this dye does not soak into the yarn and cause irregularities in the coloring.

The lever W^{10} is then thrown to the right, moving the cone of yarn away from the injector so that the needle is withdrawn from the cone.

Another point of the outer surface of the cone is then brought opposite the injector by turning the guide wheel W^{30} until the ball W^{35} enters the depression W^{33} adjacent to the one which it occupied during the first injection. The movements of the lever W^{10} and the lever P^{45} are then repeated so that another portion of the cone of yarn is dyed.

The guide wheel W^{30} is turned so as to bring the ball W^{35} successively into each of the depressions W^{33} , and after each turning of the wheel another injection is made in the manner already described. The lever W^{17} is then moved so as to shift the frame W^8 along the cross bars W^{15} and W^{16} . If dur-

ing the first series of injections the frame W^8 was set with the plunger W^{22} in the recess W^{20} ; it is now moved to bring the plunger into the recess W^{21} ; or if the plunger 5 was first in the recess W^{21} , the frame W^8 is now moved to bring it into the recess W^{20} . The guide wheel W^{30} is again turned to bring the ball W^{35} into each of the depressions W^{33} successively, and in each position 10 of the guide wheel another injection is made. This completes the spotting of the yarn of the cone C, which may then be removed and replaced by a fresh one.

The result of the operation described may 15 best be understood from the development of the outer surface of the cone C, which is shown in Fig. 13. In that view, the points of the surface of the cone from which injections have been made are indicated by dotted circles. Injections were made at three 20 series of points *a*, *b*, *c*, while the plunger W^{22} was in contact with the recess W^{20} . These three series of points correspond to the depressions W^{33} in the three helical portions 25 W^{40} , W^{41} , W^{42} of the groove W^{32} . The points of the series *a* and *b* lie along one lay of the yarn and the points of the series *c* along the other lay of the yarn. Injections have been made at three similar series of 30 points *a'*, *b'*, *c'*, while the plunger W^{22} was in contact with the recess W^{21} . As a result of the injections at these points, six portions of the cone of yarn have been dyed. Each 35 of the dyed portions D is long and comparatively narrow and extends in the direction of one of the lays of the yarn, as best seen in the side views, Figs. 11 and 12. Each dyed portion extends from the outer surface of the cone C to its inner surface (i. e., 40 its surface in contact with the core C^2) in a direction inclined to the axis of the cone and perpendicular to a plane tangent to the outer surface of the cone at the outer end of the dyed portion. The sides D^1 of each dyed 45 portion are approximately straight, as seen in Fig. 3, and the ends of each dyed portion are also substantially straight, so that the area of each dyed portion is substantially uniform throughout the depth of the yarn 50 of the cone.

A cone of yarn dyed in this manner is a new article of manufacture which forms a part of my invention, which is not claimed herein as it forms the subject matter of my 55 divisional application filed June 30, 1924, Serial No. 723,430. When such a cone is unwound, the yarn is found to contain long spots where it extended longitudinally through one of the dyed portions D of the cone, and intermediate short spots where it 60 extended transversely across one of these dyed portions of the cone. When such a yarn is made into fabric, it produces a mixture of attractive appearance.

65 Among the advantages of the machine

which has been described is its adjustability which enables it to operate upon differently wound cones of yarn. To adjust the machine for cones of different depths, it is merely necessary to loosen the nut J^{12} and 70 vary the longitudinal position of the needle J^2 in the chuck J^{10} . Adjustments for variations in the longitudinal position of cones on their cores may be made by loosening the set screw W^{23} and varying the longitudinal 75 position of the bar W^{16} and its recesses W^{20} , W^{21} .

In order to adjust the machine for the variations in the angles of the lays of the 80 yarn on cones wound on different machines, or on differently adjusted machines, the set screw W^{29} is loosened and the guide wheel W^{30} is removed from the shaft W^1 and replaced by a guide wheel having a groove 85 with portions that correspond to the lay of the yarn on the new cone. Furthermore, guide wheels may be supplied with the machine for positioning a cone to produce any predetermined arrangement of the portions dyed. In this way, the position and extent 90 of the dyed portions of a cone may be so predetermined in accordance with the winding of the cone and the manner in which the yarn is to be knitted or otherwise formed into fabric that, under any conditions of 95 winding and knitting, a fabric of a desired appearance may be obtained.

What I claim is:

1. Apparatus of the class described, comprising means for forming a stream of liquid extending into an absorbent mass, said means being arranged to permit said stream of liquid to expand laterally throughout its length by absorption into the mass. 100

2. Apparatus of the class described, comprising means for injecting under pressure a limited quantity of liquid into an absorbent mass to form a stream of liquid extending into the mass, said means being arranged to permit said stream of liquid 105 to expand laterally throughout its length by absorption into the mass. 110

3. Apparatus of the class described, comprising a nozzle, a support for an absorbent mass, means for causing relative movement 115 between said support and said nozzle to press the nozzle against the surface of the mass, and means for forcing under pressure a limited quantity of liquid into the mass through the nozzle. 120

4. Apparatus of the class described, comprising a nozzle, a support for an absorbent mass, means for causing a relative approaching movement between said support and the nozzle, means for stopping said approaching movement when the nozzle is pressed firmly against the surface of the mass and means for forcing under pressure a limited quantity of liquid into the mass through 125 the nozzle. 130

5. Apparatus of the class described, comprising a nozzle, a support for an absorbent mass, means for causing relative approaching movement between the support and the nozzle, and means adapted to engage the surface of the mass and thereby stop said movement when the nozzle is pressed firmly against the mass.
6. Apparatus of the class described, comprising a nozzle, a support for an absorbent mass, means for causing a relative approaching movement between said support and the nozzle, and a stop spaced laterally from the end of the nozzle and adapted to engage the surface of the mass and thereby stop said approaching movement when the end of the nozzle is pressed firmly against the mass.
7. In apparatus of the class described, the combination of means adapted to open a narrow passage into an absorbent mass and formed to permit lateral spreading of liquid from said passage, and means adapted thereafter to direct liquid into said passage through the outer end thereof and formed to prevent spreading of the liquid over the surface of the mass.
8. In apparatus of the class described, the combination of a nozzle having a contact surface at its outer end, and a needle projecting from the contact surface of the nozzle and formed to provide a longitudinal passage communicating with the discharge opening of the nozzle and to permit lateral egress from said passage substantially throughout the length of the projecting portion of the needle.
9. Apparatus for injecting dye into a mass of textile, comprising a nozzle containing a hole, and a needle projecting from said nozzle and having an open longitudinal groove, one end of which is in communication with said hole.
10. Apparatus for injecting dye into a mass of textile, comprising a nozzle having a flat outer end and containing a hole, and a needle fixed in said nozzle projecting beyond the outer end thereof, and having an open longitudinal groove extending substantially throughout its length and communicating with the hole of the nozzle.
11. Apparatus for injecting dye into a mass of textile, comprising a nozzle having a discharge orifice, and a needle extending through the discharge orifice in the nozzle and projecting therefrom and having an open longitudinal groove extending its entire length.
12. In apparatus of the class described, the combination of a nozzle having a contact surface at its outer end, a needle having an open longitudinal groove, and means for releasably securing said needle in the discharge opening of the nozzle so that the distance from the outer end of the needle to the contact surface may be adjusted.
13. In apparatus of the class described, the combination of a nozzle having a contact surface at its outer end, a stop fixed on said nozzle and providing an engagement surface in substantially the same plane as the contact surface of the nozzle, and a needle secured in the discharge opening of the nozzle and containing a longitudinal passage communicating therewith.
14. In apparatus of the class described, the combination of a nozzle having a contact surface at its outer end, a needle projecting from the contact surface of the nozzle and formed to provide a longitudinal passage communicating with the discharge opening of the nozzle and to permit lateral egress from said passage substantially throughout the projecting portion of the needle, and a stop fixed on the nozzle and providing an annular engagement surface spaced from the contact surface of the nozzle.
15. Apparatus of the class described, comprising a support for a wound mass of yarn, a needle having an open longitudinal groove, means for supporting said needle with its point directed into the mass of yarn and with the open side of its groove turned in a direction approximately parallel to the lay of the yarn, means for causing the relative approaching movement between the support and needle to thrust the needle into the yarn, and means for forcing liquid under pressure into the rear end of the groove in the needle.
16. Apparatus of the class described, comprising a support for a wound mass of yarn, a needle containing a longitudinal groove, means for supporting said needle with its axis directed approximately radially of said mass of yarn and with the open side of its groove turned in a plane transverse to the axis of said mass of yarn, means for causing the relative approaching movement between the support and needle to thrust the needle into the yarn, and means for forcing liquid under pressure into the rear end of the groove in the needle.
17. Apparatus for dyeing textiles comprising the combination with a receptacle for liquid dye and a support for a wound mass of yarn, of means for drawing from the receptacle a measured quantity of liquid dye insufficient in amount to dye the entire mass, and means for causing said measured quantity to penetrate through said mass so as to color only a part thereof.
18. Apparatus for dyeing textiles, comprising a receptacle for liquid dye, means providing a chamber having an intake opening communicating with the receptacle and discharge opening, means for positioning a wound mass of yarn with a predetermined part thereof in front of said discharge opening, valve means for alternately opening and closing the intake opening, and means for alternately opening and closing the discharge opening.

- closing the intake opening and the discharge opening to trap measured quantities of dye in said chamber, and means operable on the opening of the discharge opening to cause the contents of the chamber to penetrate the yarn in front of the discharge opening.
19. Apparatus of the class described, comprising an injector, a support for an absorbent mass, means for causing relative movement between the injector and the support to place the injector in operative relation with different points of the surface of the mass successively, and means for forcing a plurality of equal measured quantities of liquid through the injector under pressure.
20. Apparatus of the class described, comprising a needle containing a longitudinal passage, a support for an absorbent mass, means for causing relative movement between the needle and the support to thrust the needle into the mass, and means independent of the relative movement between the needle and the mass for forcing a measured quantity of dye through the needle.
21. Apparatus of the class described, comprising a nozzle providing a contact surface, a needle projecting from said nozzle, held in fixed relation to the contact surface thereof, and containing a longitudinal passage communicating with the discharge opening of the nozzle, means for pressing the contact surface of the nozzle against a surface of an absorbent mass, and means for forcing a measured quantity of liquid through the nozzle.
22. In apparatus of the class described, the combination with a pump and an injector adapted to direct liquid discharged from the pump into an absorbent mass, of means for suddenly opening the discharge of the pump at an intermediate point of the compression stroke of the pump.
23. In apparatus for dyeing textiles, the combination with an injector for directing liquid dye into a mass of textile to be dyed, of automatic means operable to force a limited quantity of dye through said injector and thereafter to apply a suction to said injector to withdraw any dye which may remain in it.
24. In apparatus of the class described, the combination with an injector comprising a nozzle and a grooved needle projecting from the discharge opening of the nozzle, of means operable to force a limited quantity of liquid under pressure through said nozzle and needle and thereafter to apply a suction to the entrance opening of the nozzle to withdraw any liquid which may remain in the nozzle or needle.
25. In apparatus of the class described, the combination with an injector and a chamber in communication therewith, of means operable to force liquid from said chamber into said injector, to draw air into said chamber through said injector, and to permit the escape of air from said chamber and the admission of liquid thereto.
26. In apparatus of the class described, the combination with an injector adapted to direct liquid into an absorbent mass, of a pump comprising a casing providing a chamber having an intake opening, an air vent opening and a discharge opening, a reciprocable plunger forming a closure for said chamber, and valve means operable to open said intake and air vent openings at the end of the out-stroke of the plunger and to close said openings at the beginning of the in-stroke of the plunger, and to open said discharge opening at an intermediate point of the in-stroke of the plunger and to close said opening before the end of the out-stroke of the plunger.
27. In apparatus of the class described, the combination of a pump as claimed in claim 26, and means providing a closed compression chamber communicating with the pump chamber.
28. In apparatus of the class described, a pump as claimed in claim 26, in which the valve means comprise a reciprocable sleeve having ports which register with the intake opening and the air vent opening at one end of its stroke and a port which registers with the discharge opening at the other end of the stroke.
29. In apparatus of the class described, a pump comprising a casing providing a chamber having an intake opening, an air vent opening, and a discharge opening, a reciprocatable plunger forming a closure for said chamber, a reciprocatable valve sleeve having ports which register with the intake opening and an air vent opening at one end of its stroke, and a port which registers with the discharge opening at the other end of the stroke, and a cam controlling the reciprocatory movements of the plunger and valve sleeve and formed so that the valve sleeve dwells with one of its ports in register with the discharge opening of the chamber during the final portion of the in stroke of the plunger and during the first part of the out stroke of the plunger.
30. In apparatus of the class described, a pump as claimed in claim 29, in which the cam is formed so that the portion of the in-stroke of the plunger which occurs after a port of the valve sleeve registers with the discharge opening of the chamber is more rapid than the portion of the in-stroke which occurs before said port registers with said opening.
31. Apparatus of the class described, comprising a tank, a support for an absorbent mass, a pump for forcing liquid drawn from the tank into the absorbent mass, means for operating the pump, and means

actuated by the pump-operating means for stirring the liquid in the tank.

32. Apparatus of the class described, comprising a nozzle, a grooved needle projecting from said nozzle, a support for a mass of the textile to be dyed, and means for causing relative approaching and separating movements between the nozzle and the support in a direction parallel to the needle to 10 thrust the needle into the mass on the support and to withdraw it therefrom.

33. In apparatus of the class described, the combination of an injector, a support therefor, and a support for an absorbent 15 mass, said supports being mounted for relative approaching and separating movements in a direction parallel to the axis of the injector, and the support for the mass being arranged to permit movement of the surface 20 face of the mass in a direction transverse to the axis of the injector.

34. In apparatus of the class described, the combination of an injector, a support therefor, and a support for an absorbent 25 mass, said supports being mounted for relative approaching and separating movements in a direction parallel to the axis of the injector, and the support for the mass being arranged to permit movement of the surface 30 of the mass in a direction transverse to the axis of the injector, and to arrest such movement when a predetermined point of the surface of the mass lies on the axis of the injector.

35. In apparatus of the class described, the combination of an injector and a work 40 holder mounted for relative approaching and separating movements parallel to the axis of the injector, the work holder being adapted to hold a wound mass of yarn with its axis in the same plane as the axis of the injector and transverse thereto.

36. In apparatus of the class described, the combination of an injector and a work 45 holder mounted for relative approaching and separating movements parallel to the axis of the injector, the work holder being adapted to hold a wound mass of yarn with its axis in the same plane as the axis of the injector and transverse thereto and to permit rotation of the mass about its axis.

37. In apparatus of the class described, the combination of an injector and a work 55 holder mounted for relative approaching and separating movements parallel to the axis of the injector, the work holder being adapted to hold a wound mass of yarn with its axis in the same plane as the axis of the injector and transverse thereto, to permit 60 rotation of the mass about its axis, and to arrest such rotation when a predetermined point of the surface of the mass is on the axis of the injector.

38. In apparatus of the class described, 65 the combination of an injector and a support

for a wound mass of yarn mounted to permit relative movement between the injector and the mass along the axis of the injector and relative movement between the surface of the mass and the injector in a direction 70 transverse to the axis of the injector and parallel to a lay of the yarn.

39. In apparatus of the class described, the combination of an injector and a support 75 for a wound mass of yarn mounted to permit relative movement between the injector and the mass along the axis of the injector and relative movement between the surface of the mass and the injector in a direction 80 transverse to the axis of the injector and parallel to a lay of the yarn, and means for arresting the latter movement when each of a series of regular spaced points on the surface of the mass lies on the axis of the injector.

40. In apparatus of the class described, the combination of an injector and a work 90 holder mounted for relative approaching and separating movements parallel to the axis of the injector, the work holder being 95 arranged to support a cone of yarn with its axis intersecting the axis of the injector and so inclined thereto that the side of the cone toward the injector is perpendicular to the axis of the injector.

41. In apparatus of the class described, the combination of an injector and a work 100 holder mounted for relative movement parallel to the axis of the injector and relative movement perpendicular to the axis of the injector, the work holder being arranged to support a cone of yarn with its axis intersecting the axis of the injector and so inclined thereto that the side of the cone toward the injector is perpendicular to the 105 axis of the injector.

42. In apparatus of the class described, the combination of an injector and a work 110 holder mounted for relative movement parallel to the axis of the injector and relative movement perpendicular to the axis of the injector, the work holder being arranged to support a cone of yarn with its axis intersecting the axis of the injector and so inclined thereto that the side of the cone toward the injector is perpendicular to the axis of the injector, and means for arresting the relative movement of the injector and work holder perpendicular to the axis of the injector at predetermined points.

43. In apparatus of the class described, the combination of an injector and a work 115 holder mounted for relative approaching and separating movements parallel to the axis of the injector, the work holder being arranged to support a cone of yarn with its axis intersecting the axis of the injector and to permit helical movement of the cone in a direction parallel to a lay of the yarn.

44. In apparatus of the class described,

- the combination of an injector and a work holder mounted for relative approaching and separating movements parallel to the axis of the injector, the work holder being arranged to support a cone of yarn with its axis intersecting the axis of the injector and to permit helical movement of the cone in a direction parallel to a lay of the yarn, and means for arresting such helical movement at regular space intervals.
45. In apparatus of the class described, the combination of an injector and a work holder mounted for relative approaching and separating movement parallel to the axis of the injector, a work holder being arranged to support a cross-wound cone of yarn with its axis intersecting the axis of the injector and to permit helical movements of the cone in directions which are parallel respectively to the two lays of the yarn.
46. In apparatus of the class described, the combination of an injector and a work holder mounted for relative approaching and separating movement parallel to the axis of the injector, the work holder being arranged to support a cross-wound cone of yarn with its axis intersecting the axis of the injector and to permit helical movements of the cone in directions which are parallel respectively to the two lays of the yarn, and means for arresting each of such helical movements at regular space intervals.
47. In apparatus of the class described, a work holder comprising a shaft, means for securing a wound mass of yarn on said shaft with its axis coincident with that of the shaft, a supporting bearing for the shaft, a guide wheel fixed on the shaft and having a circumferential surface containing a groove and spaced depressions therein, and a spring-pressed element fixed with respect to said bearing and engaging said groove and adapted to enter said depressions.
48. In apparatus of the class described, a work holder comprising a shaft, means for securing a wound mass of yarn on said shaft with its axis coincident with that of the shaft, a supporting bearing for the shaft permitting rotational and axial movement thereof, a guide wheel detachably fixed on the shaft and having a circumferential surface containing a groove and spaced depressions therein, and a spring-pressed element fixed with respect to said bearing and engaging said groove and adapted to enter said depressions.
49. In apparatus of the class described, a work holder comprising a shaft, means for securing a wound mass of yarn on said shaft with its axis coincident with that of the shaft, a supporting bearing for the shaft permitting rotary and axial movement thereof, a guide wheel fixed on the shaft and having a cylindrical surface containing a groove having a portion parallel to a lay of the yarn and regularly spaced depressions in said portion, and a spring-pressed element held in fixed relation to said bearing and engaging said groove and adapted to enter said depressions.
50. In apparatus of the class described, a work holder comprising a shaft, means for securing a cross-wound cone of yarn on said shaft with its axis coincident with that of the shaft, a supporting bearing for the shaft permitting rotary and axial movement thereof, a guide wheel fixed on the shaft and having a cylindrical surface containing a continuous groove having a helical portion parallel to one lay of the yarn in the cone and another helical portion parallel to the other lay of the yarn in the cone and a plurality of regularly spaced depressions in each helical portion, and a spring-pressed element held in fixed relation to said bearing and engaging said groove and adapted to enter said depressions.
51. A machine of the class described, comprising a fixed injector, and a work holder including a slide mounted for movement parallel to the axis of the injector, a shaft mounted on said slide with its axis in the same plane as the axis of the injector and transverse thereto, means for mounting a wound mass of yarn on said shaft, means for causing a reciprocatory movement of said slide, and adjustable means for limiting the movement of said slide towards the injector.
52. Apparatus of the class described, comprising an injector, a slide mounted for movement perpendicular to the axis of said injector, means for setting said slide in predetermined positions, a second slide mounted on the first slide for movement parallel to the axis of the injector, and means for mounting a cone of yarn on said second slide with its axis in the same plane as the axis of the injector and transverse thereto and with the side of the cone adjacent to the injector substantially perpendicular to the axis of the injector.

In testimony whereof I have hereunto set my hand.

HENRY E. VAN NESS.
